UNITED STATES PATENT OFFICE.

EDWARD C. STEARNS, OF SYRACUSE, NEW YORK.

DOOR-HANGER.

SPECIFICATION forming part of Letters Patent No. 268,836, dated December 12, 1882.

Application filed January 5, 1882. (No model.)

To all whom it may concern:

Be it known that I, EDWARD C. STEARNS, of Syracuse, in the county of Onondaga, in the State of New York, have invented new and useful Improvements in Door-Hangers, of which the following, taken in connection with the accompanying drawings, is a full, clear, and exact description.

This invention relates to the class of door-hangers usually designated "barn-door hangers," and which have a single carrying wheel or roller riding on a stationary track-rail above the door.

The invention consists chiefly in providing the hanger-strap with lateral arms extended across the track-rail at opposite sides of the hanger-strap, and providing the ends of said arms with suitable bearings adapted to engage the rear of the track-rail; and it also consists in uniting the aforesaid arms at their ends by a bridge, forming one of the axial supports for the carrying-roller, all as hereinafter more fully explained, and specifically set forth in the claims.

In the annexed drawings, Figure 1 is a face view of my improved door-hanger; Fig. 2, an edge view, and Fig. 3 a plan view, of the same.

Like letters of reference designate like parts in all the figures.

A represents the hanger-strap, secured to the upper portion of the door D, and projecting above the same and above the usual track-rail, T, on the side of the building, and having journaled on its end the carrying-wheel W, which travels on the aforesaid track-rail and carries the door in a suspended position. From opposite edges of the hanger-strap A project two arms, a a, which are extended across the top of the track-rail, and have journaled on their extremities a horizontal friction-roller, r, adapted to engage the rear face of the track-rail T, as best seen in Figs. 2 and 3 of the drawings. In order to brace the arms a a, and at the same time obtain an additional axial support for the carrying-wheel W, I unite said

arms by a bridge, b, which has its central or intermediate part raised sufficiently to receive through it or otherwise sustain the journal of the wheel W at the rear of said wheel.

I am aware of the use of a guide-roller sustained at the rear of the track-rail by a bar to which said roller is pivoted, and which bar is adjustably connected to arms projecting from the upper portion of the hanger-strap; but such arrangement of parts is complicated and expensive, and does not afford the requisite security to the position of the guide-roller.

Having described my invention, what I claim is—

1. The combination, with the hanger A and wheel W, of the arms a a, extended from opposite sides of the hanger across the tread of the wheel, and terminating with bearings against the rear face of the track-rail, as set forth and shown. 60

2. The combination, with the hanger A and wheel W, of the arms a a, extended from opposite sides of the hanger across the tread of the wheel, and the roller r, pivoted directly on the extremity of said arms and engaging the rear of the track-rail T, substantially as described and shown. 7c

3. The improved door-hanger consisting of the hanger-strap A, having the arms a a reaching across the track-rail T, the rollers r, pivoted on the extremities of said arms and engaging the rear of the track-rail, the bridge b, rigidly attached to the arms a a, and the wheel W, journaled on and between the hanger-strap and bridge, all constructed and combined substantially in the manner described and shown. 75 80

In testimony whereof I have hereunto signed my name and affixed my seal, in the presence of two attesting witnesses, at Syracuse, in the county of Onondaga, in the State of New York, 85 this 24th day of December, 1881.

EDWARD C. STEARNS. [L. S.]
